POCKET TABLET DISPENSER

Samuel Tapper, Maplewood, N.J.

Application June 25, 1957, Serial No. 46,726

Term of patent 14 years

(Cl. D58—12)

Fig. 1 is an exploded perspective view of a pocket tablet dispenser, showing my new design; and

Fig. 2 is a perspective view thereof shown in closed position.

I claim:

The ornamental design for a pocket tablet dispenser, as shown.
